United States Patent Office

Des. 188,117
Patented June 7, 1960

188,117

CABINET

Edgar W. Roehm, 1133 Burdsal Parkway,
Indianapolis, Ind.

Filed Apr. 6, 1959, Ser. No. 55,366

Term of patent 14 years

(Cl. D33—19)

FIG. 1

FIG. 2

FIG. 3

FIG. 4

FIG. 5

FIG. 6

Fig. 1 is a side elevational view of a cabinet embodying my new design;

Fig. 2 is a front elevational view thereof; and

Fig. 3 is a top plan view thereof.

Fig. 4 is a fragmentary perspective view of the top drawer of my cabinet;

Fig. 5 is a fragmentary front-elevational view of the pulls thereon;

Fig. 6 is a fragmentary side-elevational view thereof;

The back of the cabinet is conventionally plain.

I claim:

The ornamental design for a cabinet, substantially as shown and described.
